WAVE FORM GENERATING CIRCUITS

Carl A. Segerstrom, Winchester, Mass., assignor
to Raytheon Manufacturing Company, Newton,
Mass., a corporation of Delaware

Application October 4, 1950, Serial No. 188,426

5 Claims. (Cl. 250—27)

1

This invention relates to wave-form generating circuits, and more particularly to a circuit for producing a saw-tooth wave form.

It is well known that an extremely linear saw-tooth wave form may be produced by a vacuum tube circuit using the Miller effect. Such a circuit must be periodically deenergized, switched, or gated to return the circuit to its starting condition.

This invention discloses a saw-tooth wave-form generating circuit which is self-switching, self-triggering, or oscillatory. Briefly, this is accomplished by placing a discharge device, shown here, by way of example, as a gaseous, grid-controlled discharge device across the capacitance which feeds the signal from the plate to the control grid of the vacuum tube. When the capacitance has charged to a predetermined point, the gaseous-discharge device fires, thereby discharging the capacitance and returning the circuit to its initial starting conditions.

This invention further discloses the use of a cathode follower connected in the circuit between the plate and the capacitance which feeds the control grid of the vacuum tube. If the output of the circuit is taken from the cathode of the cathode follower, the advantages inherent in the cathode follower action may be realized; namely, a match to a low impedance load may be produced, relatively large powers may be drawn from the output, and variations in the output load will not substantially change the linearity of the Miller integrating circuit, and will produce little or no disturbance therein.

In addition, since the cathode follower is in the negative feed-back circuit between the plate and grid of the vacuum tube, any non-linearities in the amplifying action of the cathode follower, due to its use over extremely large voltage ranges, will be substantially reduced by compensation through the negative feed-back circuit of the vacuum tube.

This invention further provides means whereby a pulse may be obtained during firing of the gaseous-discharge device for use, for example, in cathode-ray tube applications as a blanking signal, and, if desired, a trigger signal may be used to terminate the duration of the sweep. Also, the sweep rate may be made extremely slow, if desired, without destroying the linearity of the wave form.

Other and further advantages of this invention will become more apparent as the description thereof progresses, reference being had to the accompanying drawing, wherein the single figure illustrates a schematic diagram of a circuit embodying this invention.

Referring now to the drawing, there is shown a vacuum tube 1, which is shown, by way of example, as a pentode having a cathode 2 which

2

is connected to ground, a control grid 3, a screen grid 4, a suppressor grid 5 which is also grounded, and a plate 6. Control grid 3 is connected through a resistor 7 to a source of potential, shown here, by way of example, as a variable tap 8 of potentiometer 9. One end of potentiometer 9 is connected to ground, and the other end thereof is connected through a resistor 10 to a source of negative potential. The screen grid 4 is connected through a resistor 11 to B+, and through a resistor 12 to ground. The plate 6 is connected through a load resistor 13 to B+, and to the grid 14 of a cathode follower amplifier 15. The plate 16 of amplifier 15 is connected to B+, and the cathode 17 thereof is connected through a load resistor 18 to ground. The cathode 17 is also connected through a charging capacitance 19 to the grid 3 of the vacuum tube 1. The terminal of capacitance 19, which is connected to the grid 3 of tube 1, is also connected to the cathode 20 of a grid-controlled, gaseous-discharge device 21. The plate 22 of device 21 is connected to the terminal of capacitance 19, which is also connected to the cathode 17 of cathode follower 15. The grid 23 of device 21 is connected to a variable tap 24 of a potentiometer 25. One end of potentiometer 25 is connected to ground through a resistor 27, and the other end thereof is connected through a resistor 26 to a source of negative potential.

The operation of the device will now be described. Assume the gaseous-discharge device 21 has just fired. The condenser 19 discharges rapidly through the gaseous-discharge device 21 until the potential difference thereacross is sufficiently low to extinguish the discharge device 21. When the discharge device 21 becomes extinguished, the grid 23 thereof regains control and prevents firing of the discharge device.

Discharge of condenser 19 tends to drive grid 3 positive, causing tube 1 to conduct heavily and hence produce a high voltage drop across plate resistor 13, thereby driving grid 14 of cathode follower 15 negative. Cathode 17 thereof follows until it differs in potential from grid 3 by the voltage at which discharge device 21 becomes extinguished. As the condenser 19 begins to charge from the source of negative potential through the potentiometer 9 and resistor 7 to one side of the condenser, and from the other side of the condenser through the cathode follower amplifier 15 to B+, the grid 3 tends to go negative and, therefore, the voltage at plate 6 rises, thereby raising the potential of cathode 17 at substantially the same rate as the voltage across condenser 19 increases. The result is that the potential difference across the charging resistor 7 remains substantially constant, and hence the rate of current flow into condenser 19 through resistor 7 is substantially constant. As a result,

the voltage across condenser 19 rises at a substantially constant rate, thereby producing a substantially linear saw-tooth wave form.

Since the charging current through resistor 7 remains substantially constant, the potential difference between the cathode 20 and the grid 23 of the gaseous-discharge device 21 remains substantially constant. However, the potential difference between the plate 22 and the cathode 20 of the gaseous-discharge device 21 increases as the charge developed across condenser 19 increases until a point is reached where the grid loses control and the gaseous-discharge device 21 fires. This again discharges the condenser 19, thereby terminating the generation of one saw-tooth wave form and initiating generation of the next.

By adjusting the variable tap 8 of potentiometer 8, the potential across the charging resistor 7 may be adjusted during the charging period, and hence the rate at which condenser 19 is charged may be adjusted. By adjusting the variable tap 24 of potentiometer 25, the point at which the discharge device 21 fires for a given setting of variable tap 8 may be adjusted, thereby adjusting the amplitude of the sweep.

When the gaseous-discharge device 21 fires and discharges condenser 19, the grid 3 moves positive, thus causing an increase in the screen current which flows through resistor 11, and thereby producing a negative excursion of screen grid 4. This negative wave form may be used as a blanking pulse during the discharge of condenser 19 between sweeps, and may be applied, for example, to a cathode-ray tube which is utilizing the saw-tooth generator as a horizontal or vertical deflection voltage source. If desired, trigger pulses may be applied to grid 23 to terminate the sweep at any desired time or periodicity.

It is to be clearly understood that the gaseous-discharge device 21 could be, for example, a simple gaseous diode instead of a grid-controlled device, said gaseous diode firing when the potential across condenser 19 reached a predetermined value.

While the signal output, as shown here, is taken from the cathode 17 of the cathode follower 15, it could, if desired, be taken from the plate 6 or directly across the condenser 19, if desired.

Furthermore, the cathode follower 15 with its resistor 18 could be eliminated altogether, and the condenser 19 connected directly from the plate 6 to the grid 3, if so desired.

This completes the description of the modification of the invention disclosed herein. However, many variations thereof will be apparent to persons skilled in the art. For example, a triode, a tetrode, or a pentagrid tube could be used in place of the pentode 4 in the Miller integrating circuit. Impedances, other than resistances, could be used in various places throughout the circuit, and the other species of the Miller integrating circuit could be used in place of the particular arrangement shown here. Therefore, it is desired that this invention be not limited to the particular details of the embodiment of the invention described herein, except as defined by the appended claims.

What is claimed is:

1. A wave-form generating circuit comprising an electron-discharge device having a cathode, a control grid, and a plate, a circuit connecting said plate to said control grid for feeding signals therebetween comprising a capacitance,

means for discharging said capacitance comprising a gaseous electron-discharge device having a cathode, a grid, and a plate, the plate and cathode of said gaseous electron-discharge device being connected to opposite sides of said capacitance, and the grid of said gaseous electron-discharge device being connected to a control voltage source.

2. A wave-form generating circuit comprising an electron-discharge device having a cathode, a control grid, a screen grid, a suppressor grid connected to said cathode, and a plate, a circuit connecting said plate to said control grid for feeding signals therebetween comprising a capacitance, means connecting said screen grid to a source of potential through a load impedance, and means for discharging said capacitance comprising a gaseous electron-discharge device.

3. A wave-form generating circuit comprising an electron-discharge device having a cathode, a control grid, a screen grid, a suppressor grid connected to said cathode, and a plate, a circuit connecting said plate to said control grid for feeding signals therebetween comprising a capacitance, means connecting said screen grid to a source of potential through a load impedance, means for discharging said capacitance comprising a gaseous electron-discharge device having a cathode, a grid, and a plate, the plate and cathode of said gaseous electron-discharge device being connected to opposite sides of said capacitance, and the grid of said gaseous electron-discharge device being connected to a control voltage source.

4. A wave-form generating circuit comprising an electron-discharge device having a cathode, a control grid, a screen grid, a suppressor grid connected to said cathode, and a plate, a circuit connecting said plate to said control grid comprising a capacitance, means for deriving a pulse from said screen grid comprising means connecting said screen grid to a source of potential, means for discharging said capacitance comprising a gaseous electron-discharge device having a cathode, a grid, and a plate, the plate and cathode of said gaseous electron-discharge device being connected to opposite sides of said capacitance, and the grid of said gaseous electron-discharge device being connected to a control voltage source.

5. A wave-form generating circuit comprising an electron-discharge device having a cathode, a control grid, and a plate, a circuit connecting said plate to said control grid for feeding signals therebetween comprising a capacitance, means for varying the charge on said capacitance comprising a gaseous-discharge device, said gaseous-discharge device having a control electrode, and means for feeding signal pulses to said control electrode to fire said discharge device.
